UNITED STATES PATENT OFFICE.

CHESTER C. OBERLY, OF CHICAGO, ILLINOIS, ASSIGNOR TO THE PULLMAN COMPANY, OF CHICAGO, ILLINOIS, A CORPORATION OF ILLINOIS.

TERMINAL BOX.

1,248,699.

Specification of Letters Patent. Patented Dec. 4, 1917.

Application filed March 10, 1916. Serial No. 83,346.

To all whom it may concern:

Be it known that I, CHESTER C. OBERLY, a citizen of the United States, residing at Chicago, in the county of Cook and State 5 of Illinois, have invented certain new and useful Improvements in Terminal Boxes, of which the following is a specification.

For train lighting purposes it is not uncommon to suspend the axle-driven generator from the truck, in which case the generator swings with the truck and thus maintains undistorted the driving connection between the axle and generator when rounding curves and in similar circumstances. 10 The wires leading from the swinging generator to the lighting system of the car must, to allow for the shifting of the position of the generator, include considerable slack and heretofore difficulty has been encountered in providing the necessary slack in the lead wires and yet guard against the wires hanging so low as to be subject to danger of contact or engagement with the roadbed, switches, etc. 15

20 To protect these lead wires from becoming damaged by flying ballast or the like it has been usual to house the same in canvas or rubber between the points of emergence from the terminal box of the generator and entrance to the car. It has been found that the housings of this character are soon cut to pieces by flying particles and rendered inefficient without frequent renewal.

It is the object of the present invention 25 to so fashion the terminal box as to take the leads from the top thereof, thus obtaining with the same slack several inches more clearance between the leads and the top of the rails and also obtaining a better disposition of the leads within the box for connection to the several terminals. A further object of the invention is to so construct the terminal box as to provide its outlet with internal threads for engagement with the 30 spiral covering of a flexible armored hose, thus enabling the use of an armored hose housing for the leads instead of the old canvas tube.

In order that the invention and the manner of its application may be readily understood a preferred embodiment of the same is set forth in the following detailed description and in the accompanying drawing upon which such description is predicated. It 35 will be obvious that the invention is sus-

ceptible of embodiment in other and varied constructions, wherefore the drawing and description are to be taken in an illustrative rather than in an unnecessarily limiting sense. In the drawing—

60 Figure 1 is a perspective view showing an axle hung generator and the connection with the car system;

Fig. 2 is a vertical section through the terminal box; and

Fig. 3 is an elevation of the terminal box with the cover plate removed.

The terminal box is indicated at 11 provided with a removable cover plate 12 and attached to the generator 13 which is driven 70 by the belt 14 from the car axle and supported upon the rods 15—15 forming a part of the truck construction. The car body is indicated at 16, the conductors to the train system at 17 and the connector box at 18. 75

A plurality of leads 19 leading from the terminals 20 within the terminal box 11 to suitable connections in the connector box 18 are of such length as to provide considerable intermediate slack and are housed with- 80 in the armored hose 21.

Heretofore it has been usual to take the leads off from the terminal box at the bottom or the sides but I prefer to make the connections at the top of the terminal box 85 in order to provide for ample slack in the leads and at the same time avoid having the same depend too low below the car body.

To accomplish this purpose and at the same time obtain an advantageous disposition of 90 the leads within the terminal box the box is provided with a goose neck outlet 22 extending from the top upwardly and laterally and terminating in an opening which is interiorly screw threaded at 23 for engagement with the spiral metallic armor of the hose 21. It will be observed that this goose neck has inwardly flaring outwardly converging walls whereby the inner terminal portions of the leads are permitted to 100 diverge fan like to their connections with the posts 24, whereby the leads are not cramped in any way at the point of connection with the terminal, the flaring goose-neck constituting in effect an upper continuation of the box itself. For greater security the ends of the armored housing may be locked within the threaded outlet 105 of the terminal box by means of the set screw 25.

I claim:

1. The combination with an axle-hung generator, and a car lighting system supplied thereby, of a terminal box having an upwardly and laterally projecting goose neck outlet, the goose neck having flaring walls converging from the terminals within the box to the outlet, and leads extending with slack from the terminals to the car system.
2. The combination with an axle-hung generator, and a car lighting system supplied thereby, of a terminal box on the generator having an upwardly and laterally projecting goose neck outlet, the goose neck being flattened in cross section and having flaring walls converging from the terminals within the box to the outlet, and leads extending from the terminals to the car system.
3. The combination with an axle-hung generator, and a car lighting system supplied thereby, of a terminal box having an upwardly and laterally projecting goose neck outlet, with a threaded terminus, the goose neck being flattened in cross section

and having flaring walls converging from the terminals within the box to the outlet terminus, slack leads extending from the terminals to the car system, and a spirally armored lead-housing threaded in engagement with the goose neck terminus.

4. The combination with an axle-hung generator, and a car lighting system supplied thereby including a junction box, of a terminal box having an upwardly and laterally projecting goose neck outlet, with an interiorly threaded terminus, the goose neck being flattened in cross section and having flaring walls converging from the terminals within the box to the outlet terminus, a plurality of leads extending from the terminals to the junction box of the car system, and a spirally armored lead-housing threaded in engagement with the goose neck terminus.

In testimony whereof I have hereunto signed my name in the presence of two subscribing witnesses.

CHESTER C. OBERLY.
